UNITED STATES PATENT OFFICE.

JOHN WILLISON, OF DERBY, ENGLAND, ASSIGNOR TO THE NATIONAL MALLEABLE CASTINGS COMPANY, OF CLEVELAND, OHIO.

COUPLING.

1,162,271.

Specification of Letters Patent. Patented Nov. 30, 1915.

Application filed February 6, 1913. Serial No. 746,559.

To all whom it may concern:

Be it known that I, JOHN WILLISON, a subject of the King of England, and a resident of Derby, county of Derby, England, have 5 invented new and useful Improvements in Couplings, of which the following is a specification, reference being had to the accompanying drawings, in which—

Figure 1 is a horizontal section of my improved coupler; Fig. 1^a is a plan thereof; Fig. 2 is a section on lines 2—2 of Fig. 1; Fig. 3 is a view similar to Fig. 1 with the knuckle in open position; Fig. 4 is a section on lines 4—4 of Fig. 1, but with the lock in 10 lock-set position; Fig. 5 is a section on lines 5—5 of Fig. 1; Fig. 6 is a section on lines 6—6 of Fig. 1 showing the parts in locked position; Fig. 7 is a horizontal section on lines 7—7 of Fig. 2; Figs. 8, 9 and 10 are 15 details of the locking block.

My invention relates to an automatic car 20 coupler of the vertical plane type and comprising a knuckle which is adapted to swing on a pivot pin carried by the coupler head 25 and to be locked in the closed position by means of a locking block adapted to be lifted vertically and then to swing or tilt on to a lock set ledge formed in the coupler head whereby the knuckle becomes unlocked and 30 free to be swung into an open position.

The main object of the invention is to provide a coupler of greater strength and durability than those at present in use, in combination with mechanism adapted both to lift 35 the lock so as to free the knuckle and to turn the latter not only to the full open position but also in a manner to have, during the first portion of the knuckle opening movement, the nose of the knuckle, for a longer 40 period than heretofore, in close proximity with the contour or face of the usual coupler guard arm, so that the coupler may better withstand the effects of wear and tear on the several parts.

According to my invention the knuckle or pivot pin is moved to a more forward position, that is to say farther away from the inner front contour or face of the coupler head, than has been the case hitherto with

couplers provided with mechanism to open 50 the knuckle to a position wherein the tail of the knuckle is beyond or outside of the inner front face of the coupler head, so that the relative distance between the knuckle in the closed or locked position and guard arm 55 is better maintained when the coupler becomes worn than is the case with couplers having knuckles pivoted in a more rearward position. The several parts are, moreover, 60 so designated that the pivot pin and its supporting ears are relieved of pulling strain by transmitting the draft stresses directly through the knuckle tail to the locking block and thence to the draw head in the direction of the line of draft. Such forward position 65 of the pivot pin of the knuckle has heretofore been impracticable with couplers having known opening mechanism, since the tail of a knuckle so pivoted will, when the 70 knuckle moves open to its full extent, travel 70 to a position outside the coupler and beyond the reach of the said opening mechanism. In moving the pivot to a forward position 1 have consequently had to devise suitable 75 mechanism for working the lock and moving in a positive manner the knuckle to its full open position.

Referring to the drawings, A is the coupler head, B is the knuckle, C the lock, D the lock lifter and E the knuckle opener. The 80 lock C, which is of heavy cross-section to enable it to withstand the draft stresses, has locking surfaces 2 and 3 substantially at right angles to each other. When the knuckle B and lock C are in locked position 85 as is indicated in Fig. 1, the pulling stresses are transmitted through the pulling lug 4, of the knuckle tail to the recessed face 5 of the lock C and to the coupler head A by the locking faces 2 and 3 which 90 bear against corresponding surfaces 6 and 7 formed on the side wall 8 and front face of the coupler cavity. The surface 6 is substantially parallel to the line of draft; while the surfaces 7, which occur above and below 95 the coupler mouth, extend laterally on either side of the line of draft X—X. The lock C has a longitudinally projecting portion or

guide 9 which coöperates with the recess 10 in the side wall 8 of the coupler head, which acts as a guide for the lock during its vertical movement. The knuckle opener E has 5 a forwardly extending arm 11 having a lug 12 thereon which coöperates with a horizontal recess 13 in the upper portion of the knuckle tail and a rearwardly extending arm 14 so shaped as to comprise a floating ful- 10 crum 15 within the shank of the coupler, and about which the opener is adapted to be turned.

The lock lifter D has a depending leg 16 which extends downwardly through the 15 opening in the bottom of the coupler cavity. Upon the leg 16 is the lug 17 which co- 20 operates with the guideway 18 on the under- side of the coupler head to guide the lifter in a vertical direction. Upon the heel of the lifter are the trunnions 19 which operate in the slide 20, adjacent the guideway 18, and are rotated therein on the trunnion bearings 21, when the lifter has been raised sufficiently to enable the lug 17 to clear the 25 guideway 18 as is best shown in Fig. 2. The lifter may be operated by any suitable means, such as a chain or other flexible member, indicated diagrammatically at 29 (Fig. 2) and connected to the eye 22 in the lower 30 end of the lifter. To permit the lifter D to rise vertically without interference with the opener E, the latter has a U-shaped central portion 23 for the reception of the head 24 of the lifter, as is shown in Figs. 1 and 3. 35 As the lifter is raised, its head 24 contacts with the projection 25 of the lock and lifts the lock vertically out of locking engagement with the knuckle tail. As soon as the lock C is released from engagement with the 40 knuckle tail by reason of its pivotal support on the top of the lifter D, its undercut shoulder 26 will be automatically tilted onto the lock-set ledge 27 which extends longitudinally of the coupler cavity as is shown in Fig. 4. If the pull on the eye 22 of the 45 lifter is continued until the lug 17 is disengaged from the guide-way 18 it will begin to swing on the trunnions 19 thereby serving as a lever for operating the opener E by en- 50 gaging the side of the opener E in the U- shaped portion 23. A further swinging movement of the lifter throws the head 24 of the lifter to the right, thus moving the 55 opener E and causing it to turn on the vertical axis of its floating fulcrum 15 and with its forward arm 11 to rotate the knuckle B, on its pivot pin F, from its closed position into the full open position. When the 60 knuckle is unlocked by reason of the lock being lifted sufficiently to allow it to swing onto the lock-set ledge 27 it will be free to open by a further movement of the lifter D and the consequent actuation of the opener E; the knuckle will of course also open on a

pull being applied to it as the cars draw 65 apart. When the lifter D is raised suffi- 70 ciently to turn on its trunnions 19 it will swing transversely of the coupler and under the rear side of the projection 25 on the lock C, as is shown in the dotted line position of 75 Fig. 2, and when the pull on the lifter is re- 80 leased, the lifter will turn back on its trunnions 19, and its lug 17 will reenter the guide-way 18, and it will fall back and assume its initial lower or inoperative posi- 85 tion. As the opener E is not attached to the lifter D it remains in the position in which it has been pushed by the lifter, until the knuckle B is again closed, by which move- 90 ment it is returned to its initial position, and such movement of the opener will turn the lifter into a vertical position so that it will be free to drop in its guide-way to its lowermost position if the lifter is not already occupying the same. 95

The locking block is formed on its under side with a beveled face 28 under which the 100 opener E, while the knuckle is swinging into the open position, passes, whereby the block is raised by the opener, from off the lock- 105 set ledge 27 and carried laterally clear there- 110 of. In Fig. 4 the block is shown in a posi- 115 tion where it is about to be raised from off the ledge 27 ready for translation by the 120 opener. As the opener subsequently returns, on the knuckle closing, the block, now rest- 125 ing upon the opener, is moved back at a level lower than that of the ledge, and as soon as the knuckle reaches its closed posi- 130 tion the locking block becomes free to fall vertically in front of the knuckle tail and thus locks the knuckle in that position, as shown in Fig. 1.

It will be seen that when the locking block has been lifted from off the ledge 27 and 105 translated by the opener it cannot descend to its lower position until the opener has moved away from underneath it and back into the position it assumes when the knuckle 110 is in the closed position. Accordingly, as 115 long as the knuckle is open and the opener pushed or drawn over as in Fig. 3, the block is retained in a raised position and thereby prevented from falling into its locking or 120 operative position behind the knuckle tail. By reason of the engagement of the lug 12 on the opener E with the recess 13 in the 125 knuckle tail, the opening and closing move- 130 ment of the knuckle will automatically control the lateral movement of the opener. 135

The chain for raising the lifter D and se- 140 cured in its eye 22 passes upward through an inlet 30 and a passage 31 formed verti- 145 cally through the lower portion of the coupler head and to the mid level thereof. This 150 passage then extends either obliquely through the upper portion of the coupler head, as indicated at 31', Fig. 2, to an open-

ing or outlet 32 on the top of the head, so that a central vertical pull can be given to the flexible member or chain, or through a port 33 in the side wall of the head so that 5 a substantially horizontal pull can be imparted to the flexible member or chain. In Fig. 2, the broken lines 29 passing from the lower end of the lifter to the openings 32, 33 indicate approximately the positions of 10 the center lines of the flexible member or chain of the two systems referred to.

It is obvious that many changes may be made in the construction and arrangement of parts of my improved coupler, without 15 departing from my invention, since

What I claim is:—

1. In a car coupler of the character described, a swinging knuckle, a knuckle opener, a floating lock adapted to be moved 20 bodily in a vertical direction and having a gravity engagement with a lifter, the said lifter having an engagement with a guide on the under side of the coupler head for guiding the lifter in a vertical direction for 25 lifting the lock, and means for moving the lifter vertically independent of the knuckle-opening mechanism to actuate the lock and for tilting it transversely of the coupler head when it is released from engagement 30 with the guide to actuate the knuckle opening mechanism.

2. In a car coupler of the character described, a swinging knuckle and knuckle opener, a floating lock adapted to be moved 35 bodily in a vertical direction independently of the knuckle opener, a lifter for the lock, a guideway on the coupler coöperating with a portion of the lifter to guide it vertically, trunnions on the lifter about which the lifter 40 is rotated to actuate the knuckle opener when the lifter is freed from engagement with the guideway.

3. In a car coupler of the character described, a swinging knuckle, a vertically and 45 bodily movable lock, a lifter for the lock, a knuckle opener having a recessed portion for engagement with the lifter and a rearwardly extending arm comprising a floating 50 fulcrum about the vertical axis of which the knuckle opener rotates.

4. In a car coupler of the character described, a lock-set ledge in the coupler cavity, a swinging knuckle, a floating lock adapted to be lifted vertically and to tilt 55 when in raised position on to the lock-set ledge, a lock lifter, and a knuckle opener, the knuckle opener comprising means operable by the lifter for simultaneously opening the knuckle and removing the lock from the 60 lock-set ledge.

5. In a car coupler of the character described, a swinging knuckle, a floating lock adapted to be moved bodily in a vertical direction, a projection on the head of the

lock, a lifter for the lock, the head of the 65 lifter being adapted to underlie the said projection and to lift the lock thereby, a knuckle opener and means for tilting the lifter transversely of the coupler head after the lock has been raised to actuate the knuckle 70 opener.

6. In a car coupler of the character described, a swinging knuckle, a lock, a lifter for the lock, and an opener actuated by the lifter and having one end positioned on the 75 coupler shank and its other end engaging the knuckle, the last-named end being adapted to be moved into a position outside of the contour face of the coupler head and thereby positively swing the tail of the knuckle 80 outside of said face.

7. In a car coupler of the character described, a swinging knuckle, a lock, a knuckle 85 opener and a device for lifting the lock and actuating the knuckle opener, the knuckle 90 opener having a forwardly extending arm coöperating with a horizontal slot in the upper portion of the knuckle tail, and a rearwardly extending arm comprising a floating fulcrum for the opener about which 95 it rotates in a vertical axis, the actuating device having an engagement with the central portion of the knuckle opener and being adapted to move it transversely of the coupler head.

8. In a car coupler of the character described, a swinging knuckle and a lock, the knuckle having an elongated tail, the said tail having, when in locked position, both 100 its front and rear faces inclined rearwardly toward the line of draft, a pulling lug on the front face of the knuckle tail intersecting the longitudinal center line of the coupler head, having surfaces for the lock upon the front wall of the coupler head, one being above and the other below the knuckle 105 opening, and a recess on the lock coöperating with the pulling lug for transmitting draft stresses through the lock to the said bearing surfaces.

9. A car coupler having a lock-set ledge in the coupler cavity, a swinging knuckle, a floating lock, a lock lifter, and a knuckle 110 opener, the lock lifter comprising means for raising the lock and seating it on the lock-set ledge, and the knuckle opener comprising means for releasing the lock from the ledge and for supporting it when the knuckle is in opened position.

10. In a car-coupler, having a knuckle; a lock; a lock-lifter; a knuckle-opener; and a lock-set seat on the coupler-head, said 115 opener being adapted to move into engagement with said lock to shift the same from the lock set seat and to maintain said lock in an elevated position while the knuckle 120 is open and to allow it to drop into locked position when the knuckle is closed.

11. In a car-coupler, having a lock, a knuckle, a lock-lifter, and a knuckle-opener, said lifter having an engagement with the lock adapted to raise said lock and shift it onto a lock-set seat, the knuckle-opener having an engagement with the lock adapted to remove said lock from said lock-set seat

and maintain it in its elevated position and allow it to drop, upon closing of the knuckle, to locked position.

JOHN WILLISON.
